UNITED STATES PATENT OFFICE.

FELIX VICTORIEN ROULEAU, OF ISLE VERTE, QUEBEC, CANADA.

MAGNETIC ORE SEPARATOR.

SPECIFICATION forming part of Letters Patent No. 296,068, dated April 1, 1884.

Application filed October 16, 1883. (No model.)

To all whom it may concern:

Be it known that I, FELIX V. ROULEAU, of Isle Verte, in the Province of Quebec and Dominion of Canada, have invented certain Improvements in Magnetic Ore Separators, of which the following is a specification.

My invention has reference to that class of machines employed for removing ferruginous or magnetic sands and ores from non-magnetic substances, which contain as the active element a revolving body having a magnetized surface to attract and retain the magnetic material.

The invention consists in certain details of construction connected with the cylinder and magnets, as hereinafter described and claimed.

Referring to the accompanying drawings, Figure 1 represents in elevation my improved cylinder, one end being represented in section on the line xx of Fig. 2. Fig. 2 represents an end elevation of the cylinder. Fig. 3 represents a longitudinal central section through one of the electro-magnets and the supporting-bar upon which it is mounted.

In proceeding to construct my separator, I first provide a central wooden axle, a , and attach to the ends thereof, in any manner which will insure the proper rigidity, two metallic extensions or end pieces, b , which are preferably made of a square form in cross-section, except at their ends, where they are given a round form, in order to adapt them to turn in the bearings or boxes by which they are sustained. Around each of the metal ends b , on the square portion thereof, I secure a metal plate, d , preferably of square or other angular form, sustaining and confining the same in place by means of collars or plates e , applied against the two sides, as shown, or by other appropriate means, the only requirement being that the plates d shall be fixed rigidly in position and compelled to revolve with the shaft. Around the periphery of the plate d , I place a circular wooden head, f , which may be made in one piece, or composed of four segments united to the central plate, d . The most convenient means of connection between these parts is that represented in Figs. 1 and 2, consisting of a series of small plates, g , applied to the opposite faces of the parts and secured by bolts or rivets, as shown. The two circular heads f are arranged concentrically upon the shaft, and are united at the periphery by means of longitudinal wooden bars h , extending from one head to the other, and secured firmly in place thereon by bolts or screws. To prevent the danger of the bars being thrown outward by the centrifugal force developed, it is preferred to encircle them at their ends by means of external hoops or bands, i , as shown in Fig. 1. For the purpose of sustaining the bars midway of their length, I apply to the middle of the axle a central wooden disk, k , or a series of spokes sustained at the center by means of washers or collars l , applied around the shaft against their side faces. On each of the longitudinal bars h , I mount a series of electro-magnets, B . Each of these magnets consists, as represented most clearly in Fig. 3, of a central core of soft iron, m , terminating at its polar extremity in a thin rectangular plate, n , and encircled by means of a coil or helix of insulated wire, o . At the lower or inner end of the helix the core is encircled by a washer of non-conducting material, p . The inner end of the core is extended through the wooden supporting-bar h , and provided at its inner end with a screw-thread and nut, q , by means of which the entire magnet is held firmly in place upon the bar. In practice I find that the best results are attained when the polar extremity n of the magnet is made about one and three-eighths inch square, and of about one-sixteenth of an inch in thickness. It is also found advisable to make the cylinder of a diameter of about two feet, and to arrange the magnets in such manner that their polar extremities will be separated from each other on all sides to the distance of about one-eighth of an inch. All the magnets will have their coils or helices connected each with the next, so that a current may be passed continuously through all the magnets on each bar. The magnets at the ends of each bar have their helices connected by suitable wires or conductors, r , to the corresponding metallic end of the shaft. The two ends of the shaft will be placed in circuit with a battery, a dynamo-electric machine, or other suitable generator of electricity, from which a strong current will thus be transmitted through the ends of the axle to the entire series of magnets. I

have found it best in practice to place about twenty-four bobbins on each bar, and to arrange about fifty bars upon each cylinder, each cylinder thus constructed presenting at 5 its periphery twelve hundred independent rectangular surfaces to attract the magnetic material.

It will be observed that when constructed as described and shown my cylinder presents 10 a practically continuous attractive surface, the magnets being arranged in close proximity to each other, both longitudinally and circumferentially of the cylinder.

I am aware that machines have been constructed with magnets arranged thereon in 15 longitudinal rows widely separated from each other, the magnets in each row being so arranged that the spaces between their edges were fully equal to the width of their faces.

20 My arrangement is advantageous, in that it subjects the material under treatment to a practically constant action of the attractive surfaces. In practice it has been found that my arrangement secures a maximum separation with a minimum expenditure of electricity.

It is manifest that the minor details of construction may be modified as desired, provided no essential departure is made from the 30 construction and mode of operation herein set forth.

In operating my cylinder, it will be employed 35 in connection with hoppers, conductor-boards, or other suitable appliances for presenting the material to be separated in close proximity to the poles of the magnets. Various apparatus for this purpose being well known in the art, and my improvement having no reference thereto, it is deemed unnecessary to illustrate 40 or describe the same in detail herein.

Having thus described my invention, what I claim is—

1. A cylinder for a magnetic ore separator, having its entire outer surface provided with radially-arranged electro-magnets, having the 4 enlarged polar extremities of rectangular form arranged in close proximity to each other, both longitudinally and circumferentially of the cylinder.

2. The central shaft consisting of the wooden 5 body and the metallic extremities, combined with the circular end plates mounted thereon, the wooden bars mounted upon the end plates, and the series of electro-magnets mounted upon said bars and electrically connected with each 5 other and with the extremities of the shaft, substantially as described and shown.

3. In a cylinder for a magnetic separator, the combination of the shaft consisting of a wooden body and angular metal extremities, 6 the angular metal plates *d*, the circular wooden heads *f*, attached thereto, the longitudinal wooden bars *h*, and the series of magnets mounted upon said bars and electrically connected with each other and with the extremities 6 of the shaft, as described and shown.

4. In combination with the cylinder having the longitudinal wooden bars *h*, the electro-magnets having their cores *n* extended inward through said bars and secured by nuts upon 7 the inner ends.

5. In a cylinder for a magnetic separator, the longitudinal wooden bars *h*, in combination with the helix *o* and the core *m*, having its outer end provided with the polar enlargement *n*, and having its inner end passed directly through the supporting-bar and secured by a nut at the inner end.

FELIX VICTORIEN ROULEAU.
